SHELF SUPPORT

Helmut R. Klaudt, Chicago, Ill.

Application July 19, 1934, Serial No. 736,135.

5 Claims. (Cl. 254—100)

My invention relates to an adjustable shelf support adapted to be supported directly between two approximately parallel upright walls without requiring nails or other fastening elements for holding it rigidly positioned.

In general, the objects of my invention are those of providing a shelf-board support which can easily be positioned and firmly anchored to two upright walls by any one; and which will then sustain heavy weights even when the said walls are not precisely parallel to each other. Furthermore, my invention aims to provide a shelf support of this class which can readily be tightened into firm gripping relation to both of the said walls by the use of a mere wire nail as a lever, and which will automatically adjust itself (during this tightening) to the extent to which the support-engaging portions of the two walls are out of parallel.

In addition, my invention aims to provide a shelf support of the above recited characteristics which will prevent the wall-engaging elements from being expanded in any direction parallel to the face of the adjacent wall, to such an extent as to reduce the firmness of the gripping; and aims to provide an exceedingly simple and inexpensive construction for such a shelf support. Moreover, my invention aims to provide a shelf support of the above recited characteristics which can readily be adjusted and installed by a single person, as distinguished from proposed prior constructions which required two persons for this purpose.

In the drawing, Fig. 1 is a plan view of a shelf support embodying my invention, showing the same as it appears when positioned between two upright walls, portions of these walls being shown in horizontal section.

Fig. 2 is an elevation of the same shelf-support, with portions of the walls shown in vertical section, and including a shelf board seated on the shelf-support.

Fig. 3 is an enlarged end elevation of the same shelf-support and of the shelf-board supported by it, taken from the line 3—3 of Fig. 2.

Fig. 4 is a horizontal section taken along the line 4—4 of Fig. 3.

Fig. 5 is a greatly enlarged and fragmentary horizontal section taken along the line 5—5 of Fig. 2, showing a position of a part of one of the thrust brackets with respect to the threaded shank element when my shelf support is effectively disposed between two upright walls which are not quite parallel to each other.

In the illustrated embodiment, my shelf sup-

port comprises two counterpart thrust members of a hollow triangular section in plan view, each of which members may be a gray iron casting. Each of these thrust members comprises two legs 1 diverging from a boss 2 provided with a threaded bore B which has its axis A bisecting the angle between the said two arms. Connecting the outer ends of these arms is bar 3 which forms the third leg of the hollow triangular formation and which has each of its end portions formed to present an outwardly opening cup C.

These two cups on each thrust member have flat bottoms C¹ disposed in a common plane at right angles to the said axis, and have their mouth ends C² in a common plane P (Fig. 1) which is parallel to and spaced laterally outward of the aforesaid plane, and the cups preferably are spaced farther apart than the outer ends of the diverging arms 1, so that a thrust on the said legs 1 toward the bar (or end leg) 3 will be received by and distributed uniformly over the bottoms of both cups. Moreover, the outer edge 3a of the said outward leg 3 is preferably spaced inwardly from the said plane, as shown in Fig. 1, for the hereinafter recited purpose.

Each of these cups preferably has its bore of a rectangular section and its longer cup walls horizontal. Socketed in each of the said cups C is a compressible element E of uniform thickness which seats on the cup bottom C¹ and projects beyond the mouth of the cup, this compressible element being desirably of a rectangular slab of a homogeneous grade of cork, cut so as to fit snugly into the cup as shown in Figs. 3 and 4.

Interposed between the two thrust members is a thrust rod R which extends axially through the bosses 2 and 2a of the said members, and which has relatively reverse threaded connections to the said bosses, the threaded connection between the thrust rod and a single one of the bosses being arranged for allowing that rod to rock in the boss. For example, if the boss 2 has its interior thread smoothly fitting the right-hand thread r on one end third of the rod R, I provide the other boss 2a with a bore B of the same pitch as the left-hand thread r¹ on the opposite end of the said rod but form this bore thread with an oversize tap. In addition, the rod R desirably has a transverse bore 5 through which an ordinary wire nail can be inserted, so that this nail can be gripped to afford a leverage for rotating the said rod.

To install such a shelf support, the two thrust

members are first adjusted (by rotating one or both thereof on the doubly threaded rod R, or by rotating this rod while both thrust members are stationary) until the outer faces of the compressible (cork) elements E on one thrust member are spaced from the outer faces of the other two compressible elements by a distance somewhat less than the previously measured spacing of the two walls which are to be spanned by my shelf support. A wire nail N is then dropped through the rod bore 5 as in Fig. 2 so that gravity will hold it in position for use as a lever to rotate the said rod further during the installing of the shelf support.

15 When the shelf support is then held between the two walls at approximately the desired height, the two thrust members can readily be moved apart by using the said nail N as a lever to rotate the rod R until both pairs of the cork facings (or compressible elements) lightly engage the two walls W with sufficient pressure to support the shelf support alone. The installer now can readily shift each of the two thrust members to positions in which each is exactly at the desired height and with the longer walls of its two cups exactly horizontal, since a light frictional gripping of the two walls by the cork elements will still permit such a shifting.

20 After this exact positioning has been effected, the installer rotates the rod still further in the same direction as before, so that the increased separation of the two hollow triangular thrust members not only will press the outward faces of each pair of the cork elements against the adjacent wall but also will compress these cork elements sufficiently to make their grip on the said walls adequate for supporting a considerable load.

25 If each of the threaded portions r and r^1 on the rod R closely fitted the thread in the boss through which that rod portion extends, the compressible elements E could only be compressed uniformly over their entire area if the opposed faces of the two walls W were exactly parallel, which is rarely the case. However, the loose fit of the thread in the boss 2a from the rod thread extending through it allows for the extent to which the laterally opposed portions of such riser walls in a closet or niche frequently deviate from exact parallelism, so that the two thrust members automatically adjust themselves to insure a firm bearing of the entire outer face of each compressible element against the adjacent wall.

30 For example, if the rod portion r in Fig. 1 is threaded for a good fit with the threaded bore of the boss 2 through which it extends, I form the bore in the companion boss by using a sufficiently oversize tap so that the other rod portion r^1 can rock somewhat in the last named bore, thereby permitting the axis a of the other boss 2a to be tilted with respect of the axis A of the entire rod R in any plane diametric of that rod as shown on an enlarged scale in Fig. 5. As the result of this provision, the loosely threaded thrust member will rock automatically about the center of its boss 2a in any plane diametric of the thrust rod so as to equalize the force to which all four of the cork elements E are pressed against the walls adjacent to them, thereby causing each of these cork elements to have its entire outward face firmly pressed against the adjacent wall.

35 Consequently, I avoid the dissatisfaction and the accidents which have occurred with previous types of somewhat allied shelf-supports in which the two presser members were connected to each other so as to maintain their outward or wall-

engaging portions rigidly in parallel planes. Moreover, by using two widely spaced compressible elements in connection with each press member and by disposing the cup connecting portion of each outward leg or bar 3 as heretofore recited, I provide a clear spacing S of considerable width between the major portion of the end bar 3 of each such member and the adjacent wall, as shown in Fig. 1, thereby permitting this end bar portion to clear considerable wall protuberances without affecting the firmness with which my shelf support is anchored to the walls.

40 So also, by having each compressible element fit into a cup which extends peripherally completely around the inward portion of such an element, instead of having such compressible elements fitted into open-ended channels, I prevent an undue expansion of these elements in all directions parallel to the face of the adjacent wall, thereby enabling me to enhance the firmness of the gripping.

45 To prevent the above described loose and tilt-permitting interfitting of one threaded portion r^1 with the threaded bore in the adjacent thrust member from unduly reducing the effective transmission of the thrust of the rod R when my shelf-support is being firmly positioned between two approximately parallel walls, I preferably limit the previously described looseness so that it will permit the thrust member to tilt about the axis of the rod through an angle a (Fig. 5) of not more than approximately two degrees.

50 As the result of the above departures from previous practice, I have found the weight-sustaining power of my shelf-support to be far greater than that obtainable with supports in which each compressible element extended for substantially the full length or width of the corresponding presser member. And even with my cork slabs of relatively small area, I can utilize the cup walls so effectively for limiting the expanding of such compressible elements that I have found the load-sustaining ability of my shelf supports unaffected by wide variations in both temperature and humidity, and also unaffected by wide variations in the smoothness of the walls.

55 However, while I have illustrated my shelf-support as used in connection with an integral shelf-board, it should be obvious without separate illustration that this shelf-support will function to equal advantage with an extensible (two-part) shelf board. So also, it will be obvious that the details of construction and arrangement above described may be varied in many respects without departing either from the spirit of my invention or from the appended claims.

60 I claim as my invention:

65 1. A shelf-support comprising two thrust members of hollow triangular shape in plan view presenting apices toward each other and having coaxial and relatively reversely threaded bosses at their said apices, the outer leg of each triangular thrust member having both end portions thereof formed as outwardly opening cups presenting their mouth ends in a common plane spaced outwardly from the portion of that leg between the said cups; four flat compressible members respectively socketed in the said cups and projecting to a uniform distance beyond the mouth ends of the said cups; and a shank connecting the two thrust members and extending axially through both of the said bosses; the shank having a threaded portion closely fitting the thread in one of the bosses, and having a

- relatively reversely threaded portion loosely fitting the thread in the other boss so as to permit a tilting of the said other boss with respect to the axis of the said shank.
5. A shelf-support comprising an axially straight rod having a right-hand thread and a left-hand thread extending respectively from opposite ends of the rod toward its mid-length, and two counterpart thrust members respectively threaded on the said end thread portions of the rod, the threading in one thrust member being a close fit to the rod thread extending through it and the threading on the other thrust member being sufficiently loose on the rod thread extending through it to permit the said other thrust member to tilt about the axis of the said rod through an angle of a few degrees only; each thrust member having its outward end formed to present feet symmetrically disposed with respect to the axis of the rod, each such foot being hollowed out as an outwardly open cup; and compressible elements each socketed in one of the said feet, the compressible elements on each thrust member presenting their outward faces in a common plane at right angles to the axis of the threaded connection of that member to the said rod.
- 5
6. A shelf-support as per claim 1, in which each of the said cups is polygonal in section and in which the part of each compressible member housed by each cup fits against the peripheral walls of the cup.
10. 3. A shelf-support as per claim 1, in which each of the said cups is rectangular in section so as to present upright end walls and relatively longer horizontal walls, the upper horizontal walls of the cups on each end leg of a thrust member being disposed in a common plane so that one end of a shelf-board will seat flatwise conjointly on the said upper walls.
15. 4. A shelf-support as per claim 1, in which each leg of the diverging legs of a thrust member has its outer end connected to the adjacent cup approximately at the back of the said cup, whereby thrust on the said legs is distributed approximately uniformly through the cups over the outward faces of the compressible members housed by them.
